UNITED STATES PATENT OFFICE.

OTTO W. SCHAUM, OF PHILADELPHIA, PENNSYLVANIA.

DESIGN FOR A JACQUARD-LEVER.

SPECIFICATION forming part of Design No. 33,295, dated October 2, 1900.

Application filed May 31, 1900. Serial No. 18,677. Term of patent 14 years.

To all whom it may concern:

Be it known that I, OTTO W. SCHAUM, a citizen of the United States, residing at Philadelphia, in the county of Philadelphia and State of Pennsylvania, have invented and produced a new and original Design for Jacquard-Levers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

5 In the accompanying drawings, wherein like letters of reference designate corresponding parts, I have fully illustrated my invention.

In said drawings Figure 1 is a top plan view 5 of my jacquard-lever. Fig. 2 is a view in side elevation of said jacquard-lever, and Fig. 3 is an enlarged detail sectional view on the line $x-x$ in Fig. 1.

A compound lever comprising two rigidly connected members or sections, the one of which being the yoke member, consists of two substantially-parallel bars connected by rods and the other of which, being the arm member, projects from one of said rods and crosses another thereof, is what constitutes the essential or salient feature of my design.

The two sections or members of my jacquard-levers are designated by the reference characters a and b . The member a comprises two substantially-parallel bars c d , which are connected at or near one extremity by a rod or elongated plate e and intermediately between its ends by a tubular rod f and each of which has an outwardly-projecting trunnion g near its other extremity. The end portions of the bars, where the trunnions are dis-

posed, are thickened or reinforced, as at h , and the rod or elongated plate e , which connects said bars, has a longitudinal slot or slots i formed in it. The member b consists of a 45 single bar, which in elevation appears perfectly straight, but which in side view is seen as having its rear end slightly curving downwardly, as at j . Said bar has longitudinal side ribs k , which extend from points near 50 its rear end forwardly, the extreme portion of said bar, however, being devoid of the ribs and perfectly plain and flat, as at l . The rear end of the bar is shaped to provide a bearing m . This bearing comprises an integral 55 enlargement n , formed on the end of the bar, and a separable plate o , said enlargement and the plate having corresponding ears p , penetrated by bolts q . The bearing is pierced by a bore r , which receives the tubular rod f of the member a of the lever. Where the bar crosses the plate e , it is provided with two laterally-projecting and integral ears s , each of which has an orifice t , that is penetrated by a bolt u , that also penetrates the 60 slot or one of the slots i .

v is the fulcrum-shaft for the lever, said shaft extending through the tubular rod f and protruding therefrom at both of its ends.

Having thus fully described my invention, 70 what I claim as new, and desire to secure by Letters Patent, is—

The design for a jacquard-lever, substantially as herein shown and described.

In testimony that I claim the foregoing I 75 have hereunto set my hand this 17th day of November, 1899.

OTTO W. SCHAUM.
